UNITED STATES PATENT OFFICE.

JOHN WILSON, OF BOSTON, MASSACHUSETTS, ASSIGNOR TO WILSON & HUGHES,
OF SAME PLACE.

DESIGN FOR SEWING-MACHINE COVERS.

Specification forming part of Design No. 5,313, dated October 10, 1871.

To all whom it may concern:

Be it known that I, JOHN WILSON, of Boston, in the county of Suffolk and State of Massachusetts, have invented certain Improvements in Design for Sewing-Machine Covers in five pieces, of which the following is a specification:

My design consists of a rectangular box for inclosing the upper portion of the mechanism of a sewing-machine, which box or case is composed of five pieces, each of which is provided on its exposed side with an imitation panel cut into the same by any suitable means, thereby giving the completed case the appearance of a box paneled by the ordinary method, as will hereinafter more fully appear.

In the drawing, A represents the case or cover, which is composed of five pieces, B B B B B, each of which consists of a single piece. D represents an imitation panel sunken into the outer

side of each piece, thus giving the cover the appearance of a box paneled in the usual manner; while in reality, having but five pieces in its entire construction, it is much cheaper, stronger, and more simple than the old form, in which each side consists of at least five pieces.

Having thusfully described my invention, what I claim as new, and desire to secure by Letters Patent, is—

The design for a sewing-machine cover in five pieces, each of which is provided with an imitation panel, substantially as shown and described.

In testimony whereof I have signed my name to this specification in the presence of two subscribing witnesses.

JOHN WILSON.
